Primary Examiner — Susan Bennett Hattan*Assistant Examiner* — Marie Fast Horse(74) Attorney, Agent, or Firm — Bacon & Thomas, PLLC(57) CLAIM

The ornamental design for a handheld fan, as shown and described.

DESCRIPTION

FIG. 1 is a perspective view of a handheld fan showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings depict portions of the handheld fan that form no part of the claimed design.

1 Claim, 6 Drawing Sheets(56)
